UNITED STATES PATENT OFFICE.

WALTER E. F. BRADLEY, OF LOS ANGELES, CALIFORNIA, AND ALONZO B. BRADLEY,
OF NEW YORK, N. Y.

ELECTRIC-FURNACE CONSTRUCTION.

1,411,158.

Specification of Letters Patent. Patented Mar. 28, 1922.

Application filed August 27, 1918, Serial No. 251,666. Renewed August 26, 1921. Serial No. 495,720.

To all whom it may concern:

Be it known that we, WALTER E. F. BRADLEY and ALONZO B. BRADLEY, both citizens of the United States, and residing, respectively, in Los Angeles, county of Los Angeles, State of California, and in the city, county, and State of New York, have invented certain new and useful Improvements in Electric-Furnace Construction, of which the following is a specification.

Our invention relates in general to electric furnaces, and more particularly to those of the electric arc type for metallurgical operations. In a more limited sense, the invention is especially applicable to electric arc furnaces for performing metallurgical reduction by means of a gaseous reducing agent, and a construction of the furnace for this particular purpose will perhaps serve 20 as the best example to illustrate the principles involved in the invention.

Furnaces of the type above set forth require a main crucible or hearth to receive the charge of, for example, ore and flux, 25 an opening or passageway through which the charge may be introduced, electrodes for developing heat within the interior chamber of the furnace, a tuyere or some form 30 of device for applying the gaseous reducing agent to the charge, and an opening or passageway through which the slag and reduced metal may be discharged from the furnace. It is not always necessary that this latter element be separate and distinct 35 from the opening or passageway through which the charge is introduced into the furnace for treatment. In the operation of the furnace the electrodes must be suitably supplied with electric power and must be capable 40 of adjustment to maintain the proper respective positions of the electrodes between which the arc is drawn. Also the supply of the gaseous reducing agent should be capable of manipulation to control the 45 application of the reducing agent to the charge with respect to regulating the rate of supply and with respect to discontinuing the supply of gas as desired, as for example on completion of the reducing operation. The discharge of the slag and reduced ore is ordinarily accomplished by a pouring action as by tilting the furnace bodily upon a horizontal axis or by rocking the furnace upon a generally horizontal base.

According to the present invention the

furnace is of generally symmetrical form or contour, preferably circular in cross section, and is rotatably supported with its main axis inclined. Upon rotating the furnace upon its inclined axis, the level of the charge remains stationary. The tuyere through which the reducing gas is to be introduced into the charge and the door through which the charge is to be poured from the furnace, are disposed in proper relation to each other and at points in the furnace wall at suitable distances from the inclined axis so that when the furnace has been turned to one position the tuyere is beneath the molten charge and the door is above the charge, in a second position both are above the charge, and in a third position the door is beneath the charge while the tuyere is above the charge. The electrodes are mounted in the upper portion 75 of the furnace so as to project into the interior chamber above the charge and they are set at the proper angle to the axis so as to gain the most advantageous deflection of the arc downward without the arc becoming interrupted. On the other hand, the electrodes are symmetrically disposed in radial planes at equal angles from each other. With this arrangement of the electrodes in symmetrical relation, we are enabled to automatically regulate the feed of the electrodes by individual controls dependent upon the respective current passing through each one. With these general principles of construction and operation in mind, the invention will be clearly understood from a detailed description of an embodiment thereof, which we have shown in the accompanying drawings.

In said drawings Figure 1 is a vertical 95 section through the furnace in the reducing position; Figure 2 is an outside view showing the furnace shifted into an intermediate position in which both the tuyere and the door are above the level of the charge; Figure 3 is an outside view of the furnace as it appears when in the pouring position; and Figure 4 is a diagram illustrating how the feed of the electrodes may be accomplished automatically.

Referring specifically to the drawings (Figure 1) 10 indicates the inner lining of highly refractory material, 11 the backing thereof of which may for example be fire brick, and 12 the outer shell of sheet metal. As 110

shown in the present example, the furnace has an intermediate cylindrical portion and upper and lower conical portions, the common axis of these parts being inclined to the vertical, with the lowest element of the conical surface horizontal. The relation between the altitude and base of this lower cone is chosen to provide the maximum interior capacity for a given radiating surface, whereas the inclination of the axis of the furnace is chosen to bring the lowermost element of the conical surface into a horizontal plane. The charge of material such as ore and flux, is represented at 13. The tuyere through which the reducing gas is supplied to the charge 13 is mounted in the lower conical wall of the furnace and comprises a removable carbon tube 14, inserted in a highly refractory socket or sleeve 15, communicating at the bottom with a supply pipe 16 through which the reducing gas is admitted under the control of hand valve 17. Pipe 16 is presumed to be flexibly connected with a source of gas, such as for example a natural gas main.

The charge 13 is introduced into the furnace through the inlet 18 mounted in the upper cone of the furnace body. During the reducing action the gas admitted through the tuyere 14 passes upwardly through the charge and the gaseous products rising from the surface of the charge rise through the interior furnace chamber and pass out through the charge inlet 18.

In the example selected for purposes of illustration, three phase alternating current is employed, with one electrode for each phase. The electrodes are indicated at 19, and their supply conductors at 20 leading off from the three phase cable 21. As seen clearly in Figure 1, the electrodes are inclined to the main axis of the furnace, the construction being such as to deflect the arc downward as far as possible with a given voltage. The desired angle is taken into consideration in determining the height of the upper cone or roof of the furnace body, so that the electrodes may pass through the furnace roof at right angles thereto. The distance at which the electrodes are disposed from the apex of the upper cone is so chosen as to bring the point toward which the electrodes converge approximately in the centre of the interior furnace chamber so as to apply heat as uniformly as possible to the charge of ore and slag. It is also to be noted that the design calls for such dimensions as to avoid projection of the electrodes into the space immediately beneath the charge inlet 18.

By referring to Figure 4, which shows one way in which the feed of the electrodes can be accomplished automatically, it will be seen that the electrodes are distributed at equal circumferential distances about the main

axis of the furnace. It has also been stated that the several electrodes have the same inclination to the main axis of the furnace. With this symmetrical arrangement, the three phase arc will be maintained between their tips, with an equal load in each electrode so long as their tips are equidistant from the imaginary point toward which they converge. Unequal consumption of one electrode may for example increase its distance from the centre with the result that its phase meets abnormally high resistance. To restore equilibrium the individual controls shown in Figure 4 may be employed. The electrodes 19 are shown in the diagram as separately supplied with current from the individual conductors 20. Each individual conductor 20 passes through or in inductive relation with a coil 22 which is connected with a solenoid coil 23, whose armature 24 actuates switch 25 against the influence of spring 26. Switch 25 may thus be caused to make contact with a terminal 27 connected with a negative line wire 28 or with a terminal 29 connected with a positive line wire 30. The circuit leading to or from the switch arm 25 comprises a conductor 31 which leads to a motor 32 from which a conductor 33 leads to a neutral line wire 34. The shaft of motor 32 carries a pinion 35 which meshes with a rack 36 on electrode 19 so that upon the motor being energized the electrode will be moved in one direction or the other depending upon the direction of the current flowing through the windings of the motor. If we assume that the current in one of the electrodes 19 has decreased so that the current induced in coil 22 is less, the current in coils 22 and 23 will be weakened so that spring 26 may pull the switch arm 25 into contact with the terminal 29. Thereupon current flows from line wire 30 into the motor 32 by way of conductor 31 which we may assume drives the motor 32 in a direction to advance the electrode. When the electrode has been advanced to the point where the current of its phase becomes normal, the increased current flowing through coils 22 and 23 has the effect of withdrawing the switch arm 25 from the terminal 29 and the motor comes to rest. Excessive current passing through electrode 19 increases the current in coils 22 and 23 to such an extent that armature 24 is caused to draw the switch arm 25 into contact with the terminal 27 and establish a circuit through motor 32 in the opposite direction, whereupon the electrode is withdrawn until its current becomes normal. With the automatic regulation described, it is apparent that the feed of the electrodes will take place during the ordinary running of the furnace without requiring the constant shifting of the electrodes by the furnace attendant. It will however be understood that while the in-

vention does not describe any particular manual adjustment and none is shown, the automatic regulation is in practice intended to be a feature additional to any suitable construction and arrangement by which the parts can be set in their normal position by the operator and by which any required manual shifting or adjustment of the electrodes can be accomplished.

10 As explained in the introduction to this specification, the furnace is designed to have a plurality of positions, and movement into these positions is accomplished by rotating the furnace about an inclined axis. To provide for this shifting operation, the furnace is supported in the embodiment shown upon a circumferential series of rollers 35, which are suitably mounted in an annular runway 36, and have resting upon them a collar 37, which surrounds the furnace and is suitably secured thereon. Power for turning the furnace may be applied for example by a pinion 38 meshing with gear ring 39 mounted on the upper face of collar 37.

25 In operation, the furnace receives its charge while in the position shown in Figure 1, in which it will be noted the inlet 18 is vertical, the tuyere 14 is at the lowest level and the door 40 is above the charge level.

30 With the arc burning between electrodes 19 and the reducing gas delivered through tuyere 14, fusion and reduction of the charge and slagging of impurities occur. Upon completion of the reducing operation, the furnace is rotated upon its inclined axis until the tuyere 14 is removed from beneath the charge but with the door still above the level of the charge, as shown in Figure 2. By having the door and tuyere less than 40 180° apart, the space below them is thus increased. The gas may then be partially or entirely shut off without danger of the molten metal running into the tuyere. The heating may be continued or not, as desired, for a further period of time with the furnace in this position, to permit the charge to become as free as possible of gas. Preferably a reduced quantity of gas is permitted to continue flowing through the tuyere 14 to 50 maintain a reducing atmosphere above the charge and avoid oxidation of the electrodes. When it is desired to pour off slag and reduced metal, the furnace is turned further toward the position shown in Figure 3, in which the door 40 is brought below the level of the charge, but with the tuyere 14 still above the charge. Figure 3 is intended to show how the charge can be completely removed from the furnace, as the door 40 preferably has its lower edge substantially in the plane of the base of the bottom cone.

55 Additions may be made either before or after pouring off the slag, for producing a particular quality of steel. It will also be

understood that it may be desired in many cases to leave a certain quantity of molten charge in the furnace and introduce the fresh charge into this. Thus the furnace would not necessarily be turned as far as shown in Figure 3 in pouring off the reduced metal. When ready for the new charge, the furnace is returned to the position shown in Figure 1, preferably by rotation in the opposite direction. The carbon tube 14 which serves as the tuyere through which the reducing gas is introduced, is removable so as to be readily replaced when necessary. The gas passing through it protects it from oxidation, and it is found to wear better than metal or any of the ordinary refractory materials. Should the supply of gas cease or fall below a certain pressure, however, while the tuyere is beneath the molten charge, the metal flows into it and solidifies. Being removable it may in such cases be easily withdrawn and replaced.

65 The illustration of three electrodes is only to show the principle of operation where a plurality of electrodes in symmetrical relation are employed. Obviously the number may be varied without departing from the principle involved. Also the current may be either alternating or direct, but alternating is preferred.

70 We claim:

1. An electric furnace comprising a furnace body, with its main axis inclined, and having a door provided in its wall at a distance from the inclined main axis, and means for rotatably supporting the said furnace body.

75 2. An electric furnace comprising in combination a generally symmetrical furnace body having a door in its wall at a point removed from the main geometrical axis thereof, and means for rotating said furnace body with its axis inclined to raise and lower said door with respect to a horizontal plane.

80 3. An electric furnace comprising a furnace body with its main axis inclined, and having a tuyere provided in its wall at a distance from the inclined main axis, and means for rotatably supporting the said furnace body.

85 4. An electric furnace comprising in combination a generally symmetrical furnace body having a tuyere in its wall at a point removed from the main geometrical axis thereof, and means for rotating said furnace body with its axis inclined to raise and lower said tuyere with respect to a horizontal plane.

90 5. An electric furnace comprising in combination a furnace body having a door and a tuyere, both of which are removed from the main axis of the furnace, and means for

95

90

95

100

105

110

115

rotatably supporting the said furnace body with its main axis inclined.

6. An electric furnace comprising in combination a furnace body having a door and a tuyere circumferentially spaced apart and both removed from the main axis of the furnace, means for rotatably supporting the furnace body with its main axis inclined, and means for turning the furnace body upon its support to raise and lower the tuyere and door.

7. An electric furnace comprising in combination a furnace body, having a door and a tuyere, circumferentially spaced apart and at different distances from the main axis of the furnace, and means for rotatably supporting the said furnace body with its main axis inclined.

8. An electric furnace comprising in combination a furnace body having a door and a tuyere circumferentially spaced less than 180° apart and at different distances from the main axis of the furnace, and means for rotatably supporting the said furnace body with its main axis inclined.

9. An electric furnace having a conical bottom and means for rotatably supporting

the same on an inclined axis with the lowest element of the conical surface horizontal.

10. An electric furnace having a body with cylindrical intermediate portion and a co-axial conical bottom, the cylindrical portion having a door with its lower edge substantially in the plane of the base of the conical surface, and means for rotatably supporting the furnace body on an inclined axis with the lowermost element of the conical surface horizontal.

11. An electric furnace for reduction of ores, comprising a furnace body with interior chamber to contain the charge, a plurality of symmetrically arranged electrodes projecting into the said interior chamber but terminating above the charge of ore therein, said electrodes being inclined toward a common axis, means for supplying current to said electrodes, and individual feed devices controlled by the current passing through the respective electrodes for maintaining their ends at equal distances from their common axis.

WALTER E. F. BRADLEY.
ALONZO B. BRADLEY.
